Atty.

UNITED STATES PATENT OFFICE.

THOMAS RHODUS, OF CHICAGO, ILLINOIS.

RHEOSTAT.

1,159,093.

Specification of Letters Patent.

Patented Nov. 2, 1915.

Application filed March 24, 1915. Serial No. 16,546.

To all whom it may concern:

Be it known that I, THOMAS RHODUS, a citizen of the United States of America, and a resident of Chicago, in the county of Cook, State of Illinois, have invented certain new and useful Improvements in Rheostats, of which the following is a specification.

This invention relates more especially to 10 that type of rheostats forming the subject matter of my prior application for patent, Serial No. 879,009, and has for its object to provide a simple and efficient structural formation and association of the parts 15 which carry the adjustable contact element or member, and by means of which said adjustable contact element is yieldingly held in contact with the annular stationary resistance element or member of the rheostat in an 20 efficient manner, all as will hereinafter more fully appear.

In the accompanying drawings: Figure 1, is a sectional plan of a rheostat having the present improvement applied. Fig. 2, is a 25 detail perspective view of the adjustable contact member and its accessories. Figs. 3 and 4, are detail perspective views illustrating modified forms of the resilient carrying means of the adjustable contact member.

Similar reference numerals indicate like parts in the several views.

Referring to the drawings, 1 designates a suitable supporting base having the usual 35 insulating slab or web 2, upon which are supported the stationary resistance element and its accessories, hereinafter described.

3, designates the inclosing shell of the rheostat of any usual and suitable construction.

4 designates the resistance element or member of the rheostat, formed by a series of flat and open spiral windings of resistance wire, wound upon an insulating 45 core ordinarily of an open ring shape the over-lapping ends of which are secured to a supporting bracket 5, on the insulating slab or web 2, aforesaid, as set forth in detail in my prior Patent No. 1,053,219, of February 18, 1915, and said core and its resistance winding have a concentric relation to the center of the rheostat as illustrated in Fig. 1.

6 designates a centrally arranged hub on 55 the insulating slab or base 2 aforesaid, in

which the handled operating shaft 7 of the rheostat is revolvably mounted.

8 designates a carrying head or yoke in which is journaled a roller or drum 9 having rolling contact with the inner surface of the 60 stationary resistance element 4, and constituting the movable contact of the rheostat. Said construction admits of the formation of a roller or drum of ample length to afford a corresponding extent of electrical 65 contact with one or more individual spirally wound strands of the wire of the resistance element 4, aforesaid.

The carrying head 8 is operatively connected to the revolvable shaft 7 aforesaid, so 70 as to move in unison therewith and in a circular path upon the interior of the stationary resistance element 4, aforesaid, and in the present improvement, is resiliently held to such bearing contact by the detail construction of parts now to be described.

10 designates a radial bar or rod fixedly attached to the revolvable shaft 7 aforesaid, with its outer end having sliding engagement in a guide sleeve 11 on the aforesaid 80 carrying head or yoke 8. Turning movement of said head or yoke 8 upon said bar or rod 10 is prevented by a transverse pin and elongated slot formation 12 of the respective parts, and the resilient outward 85 tendency of said head or yoke 8 is attained by the outward stress of a spiral spring 13 encircling the bar or rod 10, as illustrated in Figs. 1 and 2.

In the modified construction illustrated in 90 Fig. 3, the radially disposed rod or bar 10' is a fixture on the carrying head or yoke 8, and is slidingly mounted at its inner end in a transverse guide orifice in the revolvable shaft 7. Turning movement of said head or 95 yoke 8 and guide rod or bar 10' is prevented by a radial bar or rod 14, fixedly secured to the shaft 7 in spaced relation to the rod or bar 10' and having sliding engagement with guide pins 15, or like means, on the carrying 100 head or yoke 8, aforesaid. With said modified construction, a substantially counterpart spring 13 to that heretofore described will be employed to resiliently force the head or yoke 8, outwardly.

In a modified construction illustrated in 105 Fig. 4, the carrying head or yoke 8 is operatively connected to the revolvable shaft 7 in a direct manner by a resilient connecting arm or member 16, attached at its respective 110

ends to the respective parts, and having its resilient nature attained by a series of serpentine convolutions 16' formed intermediate of its length. 17 and 18 designate 5 binding posts attached to an outer portion of the insulating slab or web 2, aforesaid, and having line connections respectively with the stationary resistance element 4 and with the movable contact element 9, as illustrated in Fig. 1.

Having thus fully described my said invention, what I claim as new and desire to secure by Letters Patent, is:—

In a rheostat, the combination of a curved

resistance element formed in the main of 15 a resistance wire wound into an open series of convolutions, a rolling contact element having contact with the inner surface of said resistance element, a centrally arranged revolute shaft, a carrying head for said 20 rolling contact element, and means associated with said shaft and carrying head for holding said rolling contact element in working relation, substantially as set forth.

Signed at Chicago, Illinois, this 22nd day 25 of March, 1915.

THOMAS RHODUS.
